DESIGN FOR A COMBINATION BRUSH HOLDER AND PASTE DISPENSER

Charles W. Ward, Los Angeles, Calif.

Application November 4, 1941, Serial No. 104,015

Term of patent 14 years

To all whom it may concern:

Be it known that I, Charles W. Ward, a citizen of the United States, residing at Los Angeles, in the county of Los Angeles and State of California, have invented a new, original, and ornamental Design for a Combination Brush Holder and Paste Dispenser, of which the following is a specification, reference being had to the accompanying drawing, forming part thereof.

brush holder and paste dispenser showing my new design,

Figure 2 is a top plan view thereof, and, Figures 3 and 4 are end elevations thereof, certain parts being in changed relationship.

I claim:

The ornamental design for a combination brush holder and paste dispenser, as shown.

CHARLES W. WARD.
